UNITED STATES PATENT OFFICE.

CHESTER W. GREENE, OF EAST LYNN, MASSACHUSETTS, ASSIGNOR TO COMMONWEALTH ENGINEERING COMPANY, INC., OF LYNN, MASSACHUSETTS.

FILM-DEVELOPING BOX.

1,189,359.

Specification of Letters Patent.

Patented July 4, 1916.

Application filed June 9, 1915. Serial No. 33,086.

To all whom it may concern:

Be it known that I, CHESTER W. GREENE, a citizen of the United States of America, residing at East Lynn, in the county of 5 Essex and State of Massachusetts, have invented certain new and useful Improvements in Film-Developing Boxes, of which the following is a specification.

The present invention appertains to an 10 improved film developing box to be used in the development of photographic films, and the primary object of the invention is the provision of a device of this character by means of which the film may be developed 15 while within the box, without recourse to a dark room while a further object of the invention is the provision of simple, but effective means for locking and successively unlocking or releasing a series of drums 20 upon which the film is wound preparatory to developing.

The invention consists in certain novel combinations and arrangements of parts as will hereinafter more specifically be set 25 forth.

In the accompanying drawings I have illustrated a complete device of this character wherein the improvements of the present invention are embodied, and this 30 device is constructed according to the best mode I have so far devised for the practical application of the principles of my invention.

Figure 1 is a vertical central sectional 35 view of the developing box, with the parts in the position they occupy when a film has been wound upon the revoluble drums. Fig. 2 is a sectional view of the film holder on line 2-2 Fig. 1, looking to the left, the 40 upper portion of the cover being also illustrated to show its locking tongue. Fig. 3 is a bottom plan view of the film holder. Fig. 4 is a top plan view of the film holder.

The two parts, the cup 1 and the cover 2, 45 are preferably cylindrical in form and of a size to telescope with each other, the open end of the cover 2 fitting in the open end of the cup 1. These parts are composed of suitable material, light in weight and du-

rable, and they fit together with a water 50 tight or liquid tight joint to prevent waste of the liquid developer to be used in the process of developing.

At its open end, the interior of the cover is screw threaded as at 3, and on the inside 55 of its closed end a comparatively thin diametrically extending rib 4 is provided extending therefrom a suitable distance and formed with inclined edges 5, 5. This locking rib is designed for the purpose of holding, and releasing, a series of winding 60 spools or drums as 6, 7, 8, 9, which form a part of the film holder and in the edges of their open ends these four drums are provided with duplicate notches 6', 7', 8', 9', 65 the notches in the individual drums being arranged diametrically opposite each other so that the rib 4 may engage the pairs of notches simultaneously. In Fig. 1 it will be noted that the notches are of increasing 70 depth from the outermost drum to the innermost one so that these notches will receive the inclined edges 5, 5 of the rib 4.

The revoluble drums 6, 7, 8, 9 are arranged concentrically and will turn freely, independently of each other upon a central stud 75 10 which is passed through perforations in the bottoms of the drums and is secured by a nut or washer 11. In addition to the notches in the revoluble drums, each of the 80 drums is provided with a slot or opening as 6^a, 7^a, 8^a, 9^a, extending from near the open end of the drum to near its closed end, and it will be noted that these slots may be lined up with each other, as in Fig. 1 so that the 85 free end of a film may be passed successively through the drums from drum 6 outwardly.

Inclosing the four revoluble drums, is a fifth drum 12 which is concentric with the revoluble drums, but is held rigid with relation to these drums. A cleat 12^b on the outer surface of the drum is utilized to attach and secure the free end of the film to be wound thereon.

The drum 12 is fastened by suitable de- 95 vices, as 13 (see Fig. 2) to a base plate 14 which is a circular disk of a diameter to fit neatly but easily within the open end

of the cover 2 and pass freely over the screw threaded portion 3 of the cover and formed with notches 14' in its edge. Attached to the outer side of this base plate 5 are a pair of slideable tongues 15 and 16 that are provided with handles 15' and 16' and also with curved edge portions 15" and 16". The slide plate or tongue 16 is slotted to fit around the stud 10 and the head 17 of the 10 stud holds the plates against detachment.

The wider plate 15 is slotted at 15^b so that the narrower plate 16 may slide bodily therein and a hump 16^b on plate 16 forms a lock for the parts. Near their outer ends 15 these slide plates are also slotted, at diametrically opposite points, so that the retaining lugs 18 which are integral with but struck up from the body of the plate 14 may be passed therethrough and clamped to the 20 slide plates. These lugs are passed through their respective slots and then bent over the bottom face of the slide plates, to retain the slide plates, but it will be noted that the slots are sufficiently large to permit movement of the plates with relation to the base 25 plate and in this movement the slide plates are guided by the slots about the stud 10. The slide plates are formed with handles 15' 16' by means of which they may be pulled 30 together or pushed apart, to engage the slide plates with the screw-thread 3, or to withdraw the slide plates therefrom.

In use, the cup 1 is first filled with the developing liquid up to the desired level 35 and the cup laid aside in convenient position for use. The slots of the four revoluble drums and the drum 12 are brought in line and the exposed film is dropped into the drum 6. The free end of the film on its 40 spool is then passed successively through the slots 6" 7" 8" 9" 12", and then wrapped once around the drum 12 and the end suitably attached or fixed to the drum at 12^b. The cover 2 is now passed over the film 45 holder so that the rib 4 fits into the pairs of notches in the edges of the open ends of the revoluble drums. Now pull the two handles 15' and 16' toward each other, holding them in one hand and the cover in the other hand. The two circular edges 15" and 16" of 50 the slide plates are thus caused to engage the screw threads 3, and now the cover is turned, the film holder being held by the two handles of the slide plates, in the grasp of the other hand. The film having been 55 wrapped about the drum 12 as described, the second cover is now rotated and the first rotation wraps the film about the drum 9 and this rotation, through the connection of the slide plates with the screw thread 3, disengages the rib 4 from the notches 9"; the second rotation wraps the film about the 60 drum 8, and the successive rotations wrap the film about the drums 7 and 6, successively withdrawing the rib from the notches 65

8', 7', 6', until all the drums are wrapped with the film and the rib is withdrawn from the drums. The film is now wrapped or wound its full length on the drum, and it merely remains to submerge the film holder 70 with its cover in the cup of the developing material in which the film is developed. In this manner the drums are driven positively to wrap the film about them, and released successively as each drum is wrapped with 75 the film.

To release the plates 15 and 16 from the threads 3, spring the handle 15' past the hump 16^b, then the two plate handles may be pulled together and the ends 15" and 16" 80 so thus withdrawn from the threads.

After winding film on the drums and before cup 1 is placed over drums, developer or liquid in cup is placed into drums which are held into an inverted position and developer or liquid is poured from cup 1 into drums through notches 14'. Then cup 1 is pressed down over drums into position shown on drawing. This joint allows the air to escape but still keeps the liquid from 90 leaking out.

Notches 14' are so arranged that they will allow a liquid to be poured into outside chamber and from this chamber the liquid will work its way into the film on drums. 95 Box can then be turned end for end at intervals until proper time has expired for developing film. Then cup is to be lifted upward from drums and developing solution or liquid poured back into cup 1. After 100 developer is poured out of drums a washing and a fixing bath can be poured into drums before removing film.

What I claim is:—

1. The combination with a cover having 105 locking means, of a film holder comprising a series of independently revoluble drums, each fashioned to operatively engage with said locking means, and means causing the successive disengagement of said drums. 110

2. The combination in a film developing box of a film holder comprising a series of individually revoluble drums and a relatively non-revoluble drum, a cover for the holder, means on the cover for positively revolving the drums and means co-acting with the non-revoluble drums for successively releasing the individually revoluble drums. 115

3. The combination in a film developing box with a film holder comprising a base 120 plate and a drum rigid therewith, a series of individually revoluble drums within the outer drum, a cover for the holder having means for engaging the revoluble drums, and means carried by said base plate for 125 causing the successive releasing of said revoluble drums.

4. The combination with a cover having a locking rib of a film holder comprising a series of independently revoluble drums 130

each formed with a recess engaged by said rib, and means for causing the successive withdrawal of said rib from the drums.

5. The combination with a cover having a locking rib, of a film holder comprising a series of independently revoluble drums each formed with a recess engaged by said

rib, a base plate and a drum fixed thereon inclosing the revoluble drums, a screw thread on the cover, and slide plates carried by the base plate engaging said screw thread.

In testimony whereof I affix my signature.
CHESTER W. GREENE.
